UNITED STATES PATENT OFFICE.

SAMUEL NORMAN SILVER, OF AUBURN, MAINE.

VELOCIPED.

SPECIFICATION forming part of Letters Patent No. 293,366, dated February 12, 1884.

Application filed February 8, 1883. (No model.)

To all whom it may concern:

Be it known that I, SAMUEL N. SILVER, of Auburn, in the county of Androscoggin and State of Maine, have invented certain new and useful Improvements in Velocipedes; and I do hereby declare the following to be a full, clear, and exact description of the invention, such as will enable others skilled in the art to which it pertains to make and use the same.

10 My invention relates to improvements in velocipedes, the object being, primarily, to provide mechanism for increasing and decreasing the propelling-power and varying the speed of the machine at the will of the rider.

15 A further object of the invention is to provide a velocipede with mechanism whereby power may be applied on both sides of the axle, thus producing both a pushing and a pulling action to revolve the axle and propel

20 the machine.

25 A further object of the invention is to combine with the mechanism for revolving the axle devices for securing a rowing movement in the propulsion of the machine, adapting the latter to be operated both by the hands and feet of the rider or riders.

With these ends in view the invention consists in the combination, with suitable guides, of an adjustable block connected to the axle 30 and provided with devices for sliding said block within its guides.

The invention further consists in the combination, with an axle provided with a drum loosely mounted thereon, of a movable block 35 suitably supported between guides, a band or other flexible connection between said drum and block, and spring mechanism arranged relative to said drum and adapted to wind said band thereon.

40 The invention further consists in the features of construction and combinations of parts hereinafter fully described, and pointed out in the claims.

In the drawings, Figure 1 represents a plan view of a three-wheeled velocipede constructed 45 in accordance with my invention. Fig. 2 represents a side view of same. Fig. 3 is a detached view of the adjustable block and its supporting-guides and adjusting devices. Figs. 50 4, 5, and 6 represent parts detached. Fig. 7 is a plan view of a four-wheeled velocipede

having my improvements applied thereto. Fig. 8 is a side elevation of Fig. 7. Fig. 9 represents a detached view of the winding-drum of Fig. 7 and its connections. Fig. 10 55 represents a side elevation of a further modification of my improvement. Fig. 11 is a rear view, and Fig. 12 a plan view, of the same. Fig. 13 represents a modification of the devices for adjusting the blocks. 60

A represents the frame of the machine, provided on each side, near its rear end, with pendent bearings *aa* for an axle or propelling-shaft, B, and at its forward end with a sleeve-bearing, *a'*, to receive the spindle *c* of a yoke, 65 C, the latter carrying a guide-wheel, D, and provided at its upper end with a cross-bar, *d*.

E E represent the carrying or propelling wheels of the machine, secured upon the axle B.

F represents a double drum having guard-flanges *f*, and mounted loosely upon the center of the axle B, and held therein in one side by a collar, *b*, formed upon the axle, and at the opposite side by a ratchet-wheel, *b'*, rigidly secured upon the axle. The drum F, on 70 the side adjacent to the ratchet-wheel *b'*, is provided with a pawl, *b²*, and spring *b³* for holding the pawl in contact with the wheel *b'*.

Upon one side of the drum F is secured one 75 end of a strap, band, or other flexible connection, G, the other end of the same being secured to the ring or loop *h* of the adjustable block H. Upon the other side of the drum F is secured one end of a coil-spring, I, the other end of which is attached to the end bar, *a'*, of 80 the frame.

J represents the operating-lever of the machine, fulcrumed on a rock-shaft, K, which is pivotally supported in bearings *k k* of the frame. The lever J consists of two parallel 85 bars, *j j*, which form guides, between which is arranged the block H, the latter having flanges or lips to retain it between its guides.

J' J' represent treadles secured upon arms projecting from each side of the lower end of 90 the lever J.

L represents an adjusting-screw, passing through the upper end block, *j'*, of the lever, and through the shaft K and block H, and bearing against the lower end block, *j²*, of the 100 lever J. The adjustable block H is interiorly threaded, and the upper end of the screw L is

provided with a crank, l , by means of which the screw is turned to adjust the block H near to or away from the fulcrum of the lever J .

5 M represent arms projecting from each side of the upper end of the lever J , to receive pivotal pendent handles N N . The lower ends of the latter are connected by rods n to the ends of the cross-bar d , to control the guide-wheel D .

10 O represents a rider's seat suitably supported upon the frame.

The operation of the machine as thus constructed is as follows: The lever J is operated by means of the handles N N and treadles J' J' , 15 thus unwinding the flexible band and turning the axle at each forward movement of the treadles, and rewinding the band by the action of the spring as the treadles move backward, and allowing the drum to turn loosely back 20 upon the axle and be held by the pawl-and-ratchet mechanism b' , b^2 , and b^3 . When it is desired to increase the power, the leverage upon the axle or propelling-shaft is increased by adjusting the block H toward the fulcrum 25 of the lever J by means of the screw L ; and if it is desired to increase the speed of the machine and lessen the power, the leverage on the axle is decreased by adjusting the block H away from the fulcrum. Thus the machine 30 may be adapted to roads of different kinds—increased power being obtained for a rough road and increased speed where the road is smooth and even.

In Figs. 7, 8, and 9 is illustrated an application of my improvements to a four-wheeled velocipede adapted to be operated by two riders. In these three figures several important modifications of the device illustrated in Fig. 1 are shown. In this modified construction two rotating drums are employed, 40 and two operating-levers, each carrying two adjustable blocks, and having double connections with the axle and drum-shaft, operating to both push and pull the latter, thus preventing the reaction of the shaft and carrying-wheels and avoiding the strain to which the parts might be liable where only single connections were employed.

45 A^4 A^4 represent the drums, arranged one on either side of the center of the axle, the inner portions, a^4 a^4 , of said drums carrying the retracting-springs a^5 a^5 , and the outer portions, a^6 a^6 , carrying the belts or bands B^4 B^5 , said bands being wound on their respective drums. The inner bands, B^4 B^4 , are connected to the 50 ends of rigid connecting-rods C^4 C^4 , the opposite ends of the latter being pivotally connected to adjustable blocks D^4 D^4 , arranged above the fulcrum of the levers E^4 E^4 . These levers are of the same construction as the levers shown in Fig. 1, already described, to serve as guides for the block, and are arranged one on each side of the frame A , and fulcrumed in elongated bearings e^4 e^4 of said frame, to permit a sliding movement of the levers. The outer bands, B^5 B^5 , connect with blocks F^4 F^4 ,

arranged below the fulcrum of the levers E^4 E^4 . The blocks D^4 D^4 are adjusted by means of screws G^4 G^4 passing through the blocks and through the top blocks, d^4 d^4 , of the levers, 70 and bearing at their lower ends against the end blocks of the levers. Each of said screws G^4 is provided at its upper end with a bevel-gear wheel, g^4 , adapted to mesh with vertical bevel-gear wheels g^5 g^5 , mounted on a transverse crank-shaft, g^6 , passing through a tube, g^7 , connecting the levers and carrying the operating-handles H^4 H^4 , connected with a cross-bar of the forward guide-wheels by rods h^4 h^4 . The ends of the shaft g^6 are provided with 80 cranks g^8 . By the construction thus described the driving-shaft is given both a push and pull at each stroke of the levers, and the blocks D^4 D^4 may be readily adjusted to or from the fulcrum of the levers to vary the power and speed 85 at the will of the riders.

When it is desired to operate the machine by two levers adapted to work independently and alternately, the levers E^4 may be arranged horizontally beneath the axle.

In Figs. 10, 11, and 12 I have shown a modified form of my improvement, which is adapted to be propelled by alternate movements of the feet. In these figures a backbone, A^8 , and a pivoted bow-brace, B^8 , are employed, 95 the former supporting the guide-wheel C^8 , and the latter being connected pivotally to bearings c^8 upon either side of the axle D^8 . The backbone A^8 is secured upon the axle, and supports the rider's seat a^8 . On each side of 100 the backbone is arranged a propelling lever or treadle, E^8 , fulcrumed on a shaft, e^8 , supported in bearings of a depending frame, F^8 . These levers carry the adjustable blocks G^8 G^8 and G^9 G^9 , to which are connected the straps 105 H^8 H^8 and their connections, these being two straps for each lever, wound upon each other, Fig. 10, upon the drums I^8 I^8 , secured loosely upon the axle D^8 , and each provided with a coil-spring, J^8 , arranged upon drums, and secured at their outer ends to a cross-bar, K^8 , below the axle. The ends of the straps H are secured, respectively, to the blocks G^8 G^8 and to rigid connecting-bars h^8 h^8 , the latter being secured to the remaining blocks, G^9 G^9 . The 110 backbone A^8 carries at its lower end a guide-wheel, C^8 , operated by a handle, M^8 , arranged adjacent to the seat of the machine, and supported upon the backbone by suitable braces, m^8 .

115 By the construction thus described it will be apparent that the treadles may be operated alternately to propel the machine.

The adjustment of the blocks G^8 G^8 and G^9 is obtained by means of bevel-gear mechanism shown in Figs. 10 and 11. The screws g^9 g^9 , upon which the blocks move, are provided at their inner ends with bevel-gearing g^{10} , adapted to mesh with intermediate bevel-gears, g^{11} , secured upon the shaft. A 125 crank-rod, N^9 , supported by the frame of the machine adjacent to the seat, is provided at

its lower end with a bevel-gear wheel, g^{12} , meshing with that of the shaft and adapted to adjust the blocks when the crank is operated.

In Fig. 13 is illustrated a further modification of the devices for adjusting the blocks for varying the leverage upon the axle. In this device the blocks are provided with a rack, o^9 , having a gear-pinion, o^{10} , arranged between them and adapted to be operated by any preferred means to adjust the blocks. The blocks and racks are provided with grooves to fit within the levers and be guided therein.

Having fully described my invention, what I claim as new, and desire to secure by Letters Patent, is—

1. In a velocipede having two or more wheels, the combination, with a driving shaft or axle, of the single operating lever, consisting of rigidly-connected parallel bars pivot-
ed on a rock-shaft, and having treads and handles at its respective ends, a block connected with said shaft or axle, arranged and adapted to slide between said bars, and means, as described, for adjusting said block, sub-
stantially as set forth.

2. In a velocipede, the combination, with the frame thereof, its supporting-wheels, and a driving shaft or axle, of the operating-lever pivoted on a rock-shaft, and consisting of two parallel bars, the adjustable block arranged within said bars, a screw passing through said block and rock-shaft and connections, as described, between said block and shaft, for revolving the latter, substantially as set forth.

3. In a velocipede, the combination, with the frame thereof, the driving-axle, and a rock shaft having bearings on said frame, of a lever fulcrumed between its ends on said rock-shaft, consisting of parallel rods, and having treads at its lower end and handles at its upper end, the adjustable block fitted between said rods, and the screw working in said block and the upper cross-piece of the lever, whereby the block is adjusted, substantially as set forth.

4. The combination, with the axle, of a drum loosely mounted thereon, and provided with spring mechanism and a pawl-and-ratchet device, a lever provided with an adjustable block, and a strap or band wound upon said drum and connected to said block by a rigid connecting-rod, substantially as set forth.

5. The combination, with the frame, provided with elongated bearings to receive the fulcrum of operating-levers, of levers provided with adjustable blocks suitably connected to the axle, substantially as set forth.

6. The combination, with the axle and loosely-mounted drum, of the operating-lever fulcrumed between its ends, and having an adjustable block arranged between the bars of the lever, said block being connected with the axle by a strap or band and said lever being provided with treads and handles, whereby the machine may be operated both by the hands and feet of the rider, thus obtaining a rowing movement, substantially as set forth.

7. The combination, with the axle, of a drum loosely mounted thereon, and provided with spring and pawl-and-ratchet mechanism, an operating-lever, or lever having adjustable blocks connected with said drum by straps or bands, and having treads and depending handles, the latter being connected with the guide-wheel of the machine by suitable rods, substantially as set forth.

8. The combination, with the axle, of an operating lever or levers provided both with handles and treads and a band or strap, and spring mechanism between said axle and lever, to obtain both a pulling and pushing action to revolve the axle, substantially as set forth.

9. The combination, with the main axle, of the separate operating-levers having two adjustable blocks fitted thereto and upon screw-threaded rods, provided at their inner ends with beveled gears adapted to mesh with an intermediate beveled gear secured upon the pivotal shaft, and the straps wound upon the drums upon the said axle, and their ends secured, respectively, to the forward blocks, and the rigid connecting-bars secured to the rear blocks, substantially as set forth.

10. The combination, with the axle and separate operating-levers, of connections between said axle and levers, whereby both a pulling and pushing action upon the axle is obtained, and a crank-rod arranged adjacent to the rider's seat and connected intermediately with the lever and axle connections, for adjusting the said connections to vary the power and speed of the machine, substantially as set forth.

In testimony whereof I have signed this specification in the presence of two subscribing witnesses.

SAMUEL NORMAN SILVER.
